GOLF TEE

Joseph Dreyfus, 730 Fort Washington Ave.,
New York, N.Y.

Filed July 13, 1964, Ser. No. 80,843

Term of patent 14 years

(Cl. D34—5)

FIGURE 1 is a perspective view of a golf tee showing my new design,

FIG. 2 is a top plan view thereof,

FIG. 3 is a side elevational view thereof,

FIG. 4 is an end elevational view thereof,

FIG. 5 is a perspective view of the golf tee wherein the pointer may fold into the shank of the tee,

FIG. 6 is a side elevational view thereof with the pointer arm folded downwardly,

FIG. 7 is an end elevational view of the pointer folded downwardly,

FIG. 8 is an exploded view of the golf tee wherein the pointer is attached to the tee by insertion into a slot in the head of the tee,

FIG. 9 is a top plan view thereof, and

FIG. 10 is a side elevational view of the assembled parts thereof.

I claim:

The ornamental design for a golf tee, substantially as shown and described.
